UNITED STATES PATENT OFFICE.

LUKE P. BEECH, OF WICHITA, KANSAS.

FURNACE-REGULATOR.

1,004,970.

Specification of Letters Patent.

Patented Oct. 3, 1911.

Application filed November 26, 1909. Serial No. 529,885.

To all whom it may concern:

Be it known that I, LUKE P. BEECH, a citizen of the United States of America, and a resident of Wichita, in the county of Sedgwick and State of Kansas, have invented certain new and useful Improvements in Furnace-Regulators, of which the following is a specification.

This invention relates to regulating devices for hot-air furnaces or the like and, more particularly, to regulators that control the air draft and check devices in union through the intervention of a thermostatic mechanism actuated upon by the expansion and contraction of the furnace itself pursuant to the rise and fall of the degree of heat generated within said furnace.

The object and consistency of the invention herein will be fully hereinafter described and particularly pointed out in the claims, the said consistency of the invention being duly shown in the accompanying sheet of drawings, in which,

Figure 1 is an elevation of the invention showing the same as it appears in action, with the draft open and the check closed, the same being the several positions that said draft and check occupy prior to the automatic action of the regulator when the degree of heat becomes higher than that normally desired; Fig. 2, a fragmentary elevation of my improved regulator device, this view being at right-angles to that of the regulator device seen in Fig. 1 and on a somewhat larger scale; and Fig. 3, an elevation of my improved regulator device, the same being taken on the reverse side of that seen in Fig. 1 and including a partial section of the thermostatic part of the device that intervenes between the furnace and the air draft and check actuating devices.

In describing the details of my invention, including their operation, 1 indicates the furnace or heater proper, 2 the outer shell or jacket that usually surrounds said heater with a suitable space or air-chamber intervening, 3 the hot-air pipes leading from the top of said jacket, 4 the smoke-flue leading from said heater, 5 the usual feed-door, 6 the usual ash-pit door, 7 the usual check valve or lid in said smoke-flue and 8 the usual draft-opening that is controlled by the lid 9 that pivots or hinges upwardly from said opening 8.

The parts thus far described or enumerated are all as in ordinary use and common to hot-air furnaces.

10 indicates a lever pivoted between its ends on a short shaft or stud 11 that projects laterally from a pendent supporting bracket or hanger 12, the latter being composed of a horizontal portion and two upright suspension-arms having angular-extensions, such suspension-arms and angular-extensions being adapted to engage one of the lower corners of the timber or bar 13 that is, in turn, secured to the joists 14 in proper position above the furnace. A cotter 11^a is used to conveniently place and hold the lever 10 on the stud 11. The lever 10 has at one end a short toothed arc formation 15 and a series of holes 16 is provided at the opposite end thereof.

17 indicates a toothed wheel or pinion keyed to one end of a shaft 18 that extends through the said bracket 12 at the end of the latter opposite to that in which the stud 11 is mounted and 19 is a lever or crank-arm rigidly mounted on the opposite outer end of the shaft 18.

20 indicates a spacing ring or hub between the pinion 17 and the bracket 12 to prevent any accidental contact of the said pinion with the bracket to retard the operation of the regulator. The lever 10 is likewise spaced from the bracket 12. I show a mutilated pinion 17 in the several views of the drawing, the object thereof being simply to save extraneous metal and weight, but it is obvious that a pinion with all its teeth intact can be used. The number of teeth in the arc-formation 15 and that of the teeth in the mutilated pinion duly correspond to simplify the construction of the device and are sufficient for its full scope of operation.

21 indicates a chain or other flexible device whose opposite ends are attached to the upwardly-hinged check valve or lid 7 and the upwardly-hinged draft valve or lid 9, respectively, it being coupled or connected between its said ends to the upper outer end of the lever or crank-arm 19, (as best seen in Fig. 1.) A weight 22 is placed in the chain 21 at a convenient point in the vertical parts thereof, but ordinarily above the check valve or lid 7, as seen in Fig. 1, that being the most convenient position for attachment and location. The said perforated-lever 10 with its toothed arc-formation 15, said pinion 17, said crank-arm 19 and said

weighted-chain 21 constitute practically all the elements of my improved regulator device herein, which will be recognized as extremely simple, easily operated and not liable to become deranged or out of order.

I will now take up the description of the thermostatic portion of my device, such being required to actuate said regulator through the instrumentality of the greater or lesser degree of heat in the heater portion of the furnace. This thermostatic device is composed of a vertical rod 23, a vertically-adjustable fork 24 having screw-threaded connection with a socket in the upper end of said rod, a hollow or open mouthed contact-head 25 having adjustable screw-threaded connection with the lower end of said rod, a lock-nut 26 for said contact-head 25, and a detachable pan or receptacle 27 carried by said rod 23 between its upper and lower ends. The upper forked end 24 is detachably secured in either one of the holes 16 at the outer end of the lever 10, said holes 16 being adapted to furnish the desired adjustment between said fork and lever 10 and making due allowance for any variations in the assembling of the parts of my device for use. The contact-head 25 at the lower end of the rod 23 is provided by me for the reason that its lower edge is of greater area than that of the rod itself would be and such greater area enables an increased contact, as well as a surer contact with the upper surface of the crown or dome 35 of the heater, as best seen in Fig. 3. The open mouth or hollow of the contact-head 25 encircles the small nipple or projection 28 that customarily tips the dome of an ordinary furnace heater. Said nipple or projection serves as a guide or centralizer for suspending the thermostatic portion of my device over the heater and does not interfere with its operation. The pan 27 forms a receptacle into which a quantity of sand or other like convenient matter is placed to provide a variably-disposed weight on the rod 23 and, also, on the regulator lever 10 to suit the desired adjustment of the entire device. Said pan is detachably secured on said rod by means of a set-screw 27^a or the like.

In order to more conveniently use the furnace with my improved regulator device, I provide a very simple connecting-means 55 with an indicator 36 that is located in the apartment above the cellar or basement where the said furnace is located. Such connecting-means is composed of a pair of angular-levers or bell-cranks 29 pivotally mounted at the respective opposite ends of the timber or bar 13, (as best seen in Fig. 1,) a connecting-wire or rod 30, a chain or flexible connection 31 leading over a pulley 32 from one of the bell-cranks 29 through an opening 33 in the floor 34 to said indicator

36 in said apartment above. Pulleys 35 are mounted on said bell-cranks 29, over which pulleys the chain 21 is hung and rides in the opening and closing of the several air valves 7 and 9 to suit the condition of the heat radiating from the furnace 1 and the expansion and contraction of the latter in use.

In the operation of my improved regulator device, the expansion of the furnace due to the heat within causes the rod 23 to rise, thereby actuating the lever 10, the latter, in turn, moving downward at its arc-formation 15 end and causing the pinion 17 to turn; the said pinion, in turn, causes the crank-arm 19 to move, whereby the chain 21 rides along the pulleys 35 against the heft of the weight 22 and allows the draft-lid 9 to gravitate gradually and slowly toward the draft-opening 8 for closing or otherwise 80 limiting the amount of air passing into said opening 8, and, also, raising the check lid or damper 7 for admitting air to the smoke pipe or flue 4; the said lids or dampers 7 and 9 alternately close and open to suit the 85 amount of air to pass into the flue or into the draft opening, as occasion may require in the regulating of the furnace for greater or less heat, or uniform heat in the apartments above; the indicator 36 in the apartment above will show thereon just what position the regulator and the dampers are in, so as to frequently save the operator a number of trips to the basement or cellar below where the furnace is located in the replenishing of, or other attention to the fire and the furnace. The weight 22 serves to automatically return the damper 7 to closed or closing position and to raise the draft-lid 9 to open position when the toothed sector 15 has 105 moved upward and, also, when the thermostatic device has returned to its downward position ready for action upon even the minutest expansion of the dome of the heater.

I claim:—

1. In a heating apparatus having air check and draft valves, a regulator device comprising a pivotally-hung lever having a toothed arc-formation at one end thereof, a pinion journaled in co-acting relation with said toothed arc-formation, a crank-arm projecting from said pinion to co-operate therewith, a flexible device connected intermediate its ends to said crank-arm and, also, connected at its opposite ends to the said air check and draft valves of the furnace, a weight in said flexible device and a vertical rod directly and thermally connecting the said lever with the dome of the heater.

2. In a heating apparatus having air check and draft valves, a thermostatic-connection comprising a vertical rod, a contact-head provided at the lower end of said rod, a variably-connected fork provided at 130

- the upper end of said rod and a regulator actuating-arm pivotally-mounted in relation with the heating apparatus and variably-connected with said fork, whereby the expansion and contraction of the contacting part of the heater causes the desired movements of said actuating-arm of the regulator.
3. In a heating apparatus having air check and draft devices, a thermal device flexibly-connected to said air check and draft devices and having at its lower end an open-mouthed contact-head adapted to engage the tip of the heater dome, a variably-
15 attached fork at the upper end of the rod forming a part of said thermal device, a weight pan or receptacle carried by said rod and adapted to receive sand or other loose contents capable of variable heft therein.
- 20 4. In a furnace-regulator, the combination with an arm or lever carrying a toothed arc-formation at one end thereof, a pinion engaging said arc-formation, a crank-arm connected to said pinion to cooperate therewith, a flexible device connected to said 25 crank-arm and riding over suitable pulleys for connection at its opposite ends with the air check and draft dampers of the furnace, bell-cranks carrying said pulleys, a rod connecting said bell-cranks, a flexible connection between one of said bell-cranks and a suitable indicator located in the apartment above the chamber occupied by said furnace and thermal means between said arc-formation-lever and the heater for actuating both 30 the regulator and the indicator.
